UNITED STATES PATENT OFFICE

2,665,032

NOZZLE SUPPORT AND SWITCH OPERATOR

Burdette W. Foss, Fort Wayne, and Scott L. Hunter, Ossian, Ind., assignors to Ossian Engineering Co., Inc., Ossian, Ind.

Application February 18, 1950, Serial No. 145,026

11 Claims. (Cl. 222—74)

1

This invention relates to a nozzle support and switch operator for liquid dispensers.

It is an object of the invention to provide means for supporting a hose nozzle when the dispensing switch is open to deenergize the dispensing motor.

Another object of the invention is to provide means for removing the nozzle support from supporting position when the switch is closed to start the dispensing motor.

Yet another object is to provide a nozzle supporting mechanism which is simple and inexpensive, yet one which is effective.

It is still another object of the invention to provide a combined nozzle boot and nozzle support mechanism.

These and other objects will become apparent from a study of this specification and the drawings which are attached hereto and are made a part hereof and in which:

Figure 1 is a front elevation of the mechanism with parts broken away to show the switch mechanism.

Figure 2 is a plan view of the mechanism with parts broken away to show switch and nozzle supporting mechanism.

Figure 3 is a sectional view of the switch operator taken substantially on line 3—3 of Figure 2.

Figure 4 is a sectional view of the nozzle supporting structure taken substantially on line 4—4 of Figure 2.

Figure 5 is an elevation of the nozzle boot and support viewed from the right of Figure 1.

Referring particularly to Figures 1 and 2, the numeral 1 indicates an electric motor which is utilized to drive a dispensing pump such as is described in our application, Serial No. 86,566, filed April 9, 1949, for Liquid Dispenser.

The motor is provided with a built-in switch 3 which is operated by a rotary shaft 5. An operating lever 7 is fixed to the upper end of the shaft and is provided with an open ended notch 9.

A switch housing or cover 11 is suitably attached as by screws 13 to the end bell of the motor. A nozzle boot 15 is attached to one side of this housing as by screws 17. The boot is disposed at such an angle that the nozzle spout 57 will not be retained therein if it is merely inserted therein.

To retain the nozzle therein, aligned openings 21, 23, 25 and a blind hole 27 are formed in the housing and boot, and an endwise slideable rod 29 is mounted freely therein.

The end of the rod 29, which enters hole 27, is preferably brought to a conical point 31. The

2

other end of the rod is provided with an operating knob 33 which has a downwardly directed locking ear 35. The latter is perforated at 37.

An ear 39 extends outwardly from the cover 11 parallel to ear 35 and is perforated at 41 so that when the rod is in the full line position, Figure 2, a padlock can be passed through the aligned holes 37 and 41 to hold the switch in the "off" position.

10 A strip 43 is fixed to the exterior of the cover 11 by a screw 45 and bears laterally against the motor end bell to assist in holding the cover in place.

15 A switch operator finger 47 has a hub 49 at one end which receives the rod 29 and is fixed in place thereon by pin 51. It overlies the switch lever 7 and has a depending pin 53 which enters the slot 5. Thus, as the rod 29 is moved axially, the pin 53 will rotate switch lever 7 to or from the "switch off" position shown in Figure 2. The diameter of the pin, above lever 7 is larger than the width of slot 5 so that rotation of the rod is limited in one direction by lever 7 and by the cover 11 in the other direction.

20 25 The nozzle 55 has a spout 57 which is adapted to enter the boot 15. The upper portion of the nozzle has a hook 59, or in some cases an eye, formed thereon. When the spout is pushed fully into the boot, the hook or eye is positioned to receive the end of rod 29.

Operation

Assuming that the nozzle is mounted in the 35 boot and the switch is in the "off" position, the rod 29 will engage the hook 59 to hold the nozzle in place.

When the padlock has been removed from the holes 37, 41, the operator will grasp the knob 33 and draw it to the dashed line position in Figure 2. At the same time he should grasp the nozzle or it will fall out of the boot.

This operation moves arm 47 downwardly, Figure 2, and rotates lever 7 counterclockwise to close the switch and start the motor 1. When dispensing has been completed, the nozzle spout is returned to the boot and knob 33 is returned to the full line position (Figure 2) so that the rod 29 will reenter the hook 59 and the blind hole 27, as shown in Figure 5. The conical end of the rod facilitates this reentry. The switch lever 7 will return to the "off" position and stop the motor 1.

The nozzle is thus held in the boot and if the 55 padlock is replaced in the holes 37, 41 the pump

is held inoperative and the nozzle is locked in place.

It is obvious that various changes may be made in the form, structure and arrangement of parts without departing from the spirit of the invention. Accordingly, applicants do not desire to be limited to the specific embodiment disclosed herein primarily for purposes of illustration; but instead they desire protection falling fairly within the scope of the appended claims.

What we claim to be new and desire to protect by Letters Patent of the United States is:

1. In a dispensing apparatus comprising an electric motor, a switch therefor having on and off positions and a dispensing nozzle, the combination of a housing for the switch, a nozzle boot fixed to the housing, a rod mounted for reciprocation in said housing and into and out of said boot and means on said nozzle positioned to be engaged by said rod when the nozzle is in the boot.

2. In a dispensing apparatus comprising an electric motor, a switch therefor having on and off positions and a dispensing nozzle, the combination of a housing for the switch, a nozzle boot fixed to the housing, a rod mounted for reciprocation in said housing and into and out of said boot and means forming an opening in the nozzle positioned to be entered by the rod when the nozzle is in the boot, the end of said rod being tapered to facilitate the entry thereof in the opening.

3. In a dispensing apparatus comprising an electric motor, a switch therefor having on and off positions and a dispensing nozzle, the combination of a housing for the switch, a nozzle boot fixed to the housing, a rod mounted for reciprocation in said housing and into and out of said boot, means on said nozzle positioned to be engaged by said rod when the nozzle is in the boot and means on the rod for operating the switch.

4. In a dispensing apparatus comprising an electric motor, a switch therefor having on and off positions and a dispensing nozzle, the combination of a housing for the switch, a nozzle boot fixed to the housing, a rod mounted for reciprocation in said housing and into and out of said boot, means on said nozzle positioned to be engaged by said rod when the nozzle is in the boot, a switch operating lever, a finger on the rod, a pin connecting the finger with the switch lever.

5. In a dispensing apparatus comprising an electric motor, a switch mounted thereon having on and off positions, and a dispensing nozzle, the combination of a housing for the switch, mounted on the motor, a nozzle boot fixed to the housing, a member mounted in the housing for movement into and out of said boot, means on said member adapted to engage the nozzle and hold it in the boot and means on the member in said housing, connected to operate said switch.

6. In a dispensing apparatus comprising an electric motor, a switch mounted thereon having on and off positions, and a dispensing nozzle, the combination of a housing for the switch, mounted on the motor, a nozzle boot fixed to the housing, a member mounted in the housing for movement into and out of said boot, means on said member adapted to engage the nozzle and hold it in the boot, means on the member in said housing, connected to operate said switch and means for holding said member in holding position.

7. In a dispensing apparatus comprising an

electric motor, a switch for controlling the operation of said motor, a dispensing nozzle, a nozzle boot for housing said nozzle when the same is not in use, the combination of nozzle locking means coacting with said boot for preventing removal of the nozzle therefrom, said locking means being operatively associated with said nozzle boot and movable to and from a locking position in which it prevents removal of the nozzle from said boot, and means coacting with said locking means for operation of said switch.

8. In a dispensing apparatus comprising an electric motor, a switch for controlling the operation of said motor, a dispensing nozzle, a nozzle boot for housing said nozzle when the same is not in use, the combination of nozzle locking means operatively associated with said boot for holding said nozzle in the boot, said locking means being mounted on said apparatus and arranged for movement to and from a locking position while the same is retained on said apparatus, and means operatively connected to said locking means for operation of said switch upon actuation of said nozzle for locking means.

9. In a dispensing apparatus comprising an electric motor, a switch for controlling the operation of the motor, a dispensing nozzle, a nozzle boot for housing said nozzle when the same is not in use, the combination with said nozzle of locking means having a locking position in which it prevents removal of the nozzle from the boot, said locking means coacting with said boot for retaining said nozzle in the boot, means operated by said locking means for operating said switch, and means for holding said locking means in locked position.

10. In a dispensing apparatus comprising an electric motor, a switch for controlling the operation of said motor, a dispensing nozzle, the combination of a nozzle boot for receiving the nozzle and retaining it therein when not in use, nozzle locking means including a member movable into and out of said nozzle boot, said member being movable to and from a locking position in which it prevents removal of the nozzle from said boot, and means connected to said member and with said switch to operate the same upon movement of said member into and out of said boot.

11. In an apparatus for dispensing fluids, said apparatus comprising a motor, a hose and a nozzle for controlling the dispensing of said fluid, the combination of a nozzle boot for housing said nozzle when the same is not in use, means for mounting the boot on the motor and means mounted on the motor and movable relative to said boot for supporting the nozzle in the boot, said last-mentioned means coacting with said boot to retain said nozzle therein when the same is not in use.

BURDETTE W. FOSS,
SCOTT L. HUNTER.
